UNITED STATES PATENT OFFICE.

CHARLES G. TAYLOR, OF KINDERSLEY, SASKATCHEWAN, CANADA.

RETAINING DEVICE FOR DEMOUNTABLE RIMS.

Application filed June 22, 1922. Serial No. 570,271.

To all whom it may concern:

Be it known that I, CHARLES G. TAYLOR, a subject of the King of Great Britain, residing at Kindersley, in the Province of Saskatchewan and Dominion of Canada, have invented certain new and useful Improvements in a Retaining Device for Demountable Rims, of which the following is a specification.

10 The present invention relates to a retaining device for demountable rims having for its principal object to provide readily accessible and easily operated means for retaining a demountable rim in place and allowing the same to be removed when desired.

15 A further object of the invention is to generally improve upon retaining means of this nature by providing a device which will be extremely simple and efficient in construction, reliable in operation, comparatively inexpensive to manufacture, and well adapted to the purpose for which it is designed.

20 With the above and numerous other objects in view as will appear as the description progresses, the invention resides in certain novel features of construction, and the combination and arrangement of parts as will be hereinafter more fully described and claimed.

25 In the drawing:—

Figure 1 is an elevation of a wheel embodying my invention.

Figure 2 is a section taken therethrough,

30 Figure 3 is a detailed section taken on the line 3—3 of Figure 1 on a larger scale,

Figure 4 is a detailed perspective of a bolt,

Figure 5 is a detailed perspective of a locking device, and

Figure 6 is a detailed perspective of one of supporting brackets.

Referring to the drawing in detail it will be seen that a felly 1 supports a plate 2 having legs 3 radiating therefrom and formed integral with or attached to the felly 1. A gear element 4 is rotatably mounted on the plate 2 being provided with an annular flange 5 engaged by brackets 6. This gear element 4 is provided with a beveled gear portion 7 and an internal gear portion 8. A spur gear 9 meshes with the internal gear portion 8 and is supported on a rod 10 suitably journaled in the plate 2 and terminating at one end in a square shank 11 so that a wrench may be engaged therewith. As is

indicated to advantage in Figure 1, a plurality of openings are provided in the spur gear 9 which are engagable with a locking device consisting of a rod 12 having a cross piece 13 at one end and a pin 14 adjacent the other end which is adapted to project through the apertures in the spur gear 9. A spring 15 is disposed between the pin 14 and the plate 2 and normally holds the rod 12 in a locked position, that is so that its end projects through one of the apertures in the spur gear 9.

A plurality of bolts 16 are supported slidably in the brackets 17, 18 and 19. The outer end of these bolts 16 are substantially rectangular in cross section being formed with heads 20 while the other ends thereof are threaded as at 21. The threaded ends 21 are mounted in brackets 18 and 19 and a nut 22 is mounted thereon between these brackets and is formed with a beveled gear portion 23 normally meshing with the beveled gear portion 7 of the gear element 4. The heads 20 project through the brackets 17 and prevent the rods from turning. It will therefore be seen that upon rotation of the gear element 4 by the spur gear 9 the nuts 22 will be rotated thereby moving the bolts 16 inwardly or outwardly depending upon the direction of rotation. When the bolts are moved outwardly the heads 20 are adapted to move along side of a demountable rim 25 so that the same will be held therebetween and between lip 26 permanently formed on the felly.

It is thought that the operation and construction of my invention will now be understood without a more detailed description thereof, but it is to be understood that numerous changes may be resorted to in the details of construction and in the combination and arrangement of parts without departing from the spirit of the invention as hereinafter claimed.

Having thus described my invention what I claim as new is:—

1. In combination, a felly, a demountable rim on the felly, a plate supported by the felly interiorly thereof, a gear element rotatable on the plate and including an internal gear portion and a beveled gear portion, a spur gear rotatable on the plate and engageable with the gear portion, means for rotating the spur gear, means for locking the spur gear, a plurality of bolts, brackets for receiving said bolts, nuts threadedly

mounted on said bolts, said nuts provided with beveled gear portions meshing with the beveled gear portions of said gear elements whereby the bolts may be moved in 5 and out of engagement with the demountable rim in the manner and for the purpose specified.

2. In combination, a felly, a demountable rim on the felly, a plate supported by the 10 felly interiorly thereof, a gear element rotatable on the plate and including an internal gear portion and a beveled gear portion, a spur gear rotatable on the plate and engageable with the gear portions and provided with an annular series of apertures, a 15 spring pressed bolt piercing the plate and insertible in said apertures of said spur gear

for locking the same against rotation, means for rotating the spur gear, a plurality of bolts, brackets for receiving said bolts, nuts 20 threadedly mounted on said bolts, said nuts provided with beveled gear portions meshing with the beveled gear portions of said gear element whereby the bolts may be moved in and out of engagement with the demountable rim in the manner and for the 25 purpose specified.

In testimony whereof I affix my signature in presence of two witnesses.

CHARLES G. TAYLOR.
